UNITED STATES PATENT OFFICE

ALFRED B. ESSELTINE, OF CHICAGO, ILLINOIS, ASSIGNOR TO GOODMAN MANUFACTURING COMPANY, OF CHICAGO, ILLINOIS, A CORPORATION OF ILLINOIS

APPARATUS FOR HANDLING LOOSE MATERIALS

Application filed March 4, 1926. Serial No. 92,152.

This invention relates to an apparatus for handling loose materials and has among other objects to provide a new and improved apparatus of this description for moving loose material from one point to another by means of a scraper, and for actuating, guiding and controlling the scraper, and is particularly adapted to be used in moving coal from a mine room to the entry or passageway communicating therewith for loading directly upon mine cars. That it may be used for other purposes is of course evident.

In a pending application bearing Serial Number 352,413, filed January 19, 1920, by Charles E. Davis, an apparatus of this class has been disclosed. In the present application I use the same general principle of operation as therein described but employ certain improvements for the controlling and actuating mechanism for the rope drums and guiding devices for the ropes, as will hereinafter more fully appear. My invention may be better understood by reference to the accompanying drawings.

Figure 1 is a plan view of a portable loading device embodying part of my invention, with parts broken away to show the actuating and controlling mechanism for the scraper and the means to propel and control this mechanism;

Figure 2 is a side elevation of the device shown in Figure 1;

Figure 3 is a sectional view through the front axle box showing the spring suspension of the front axle;

Figure 4 is a transverse section through the drum shaft taken on line 4-4 of Figure 1;

Figure 5 is a longitudinal section taken on line 5-5 of Figure 4;

Figure 6 is an enlarged fragmentary sectional view of the drums shown in Figure 4;

Figure 7 is an enlarged fragmentary view of the front end of the guide chute showing one arrangement of the guide sheaves for the control ropes;

Figure 8 is a similar view of the front end of the guide chute showing another arrangement of the guide sheaves;

Figure 9 is a section through one of the removable sheaves;

Figure 10 is a view showing a mine room with one form of the device embodying the invention wherein the material is being gathered from one side of the device;

Figure 11 is a view showing a mine room with one form of the device embodying the invention wherein the material is being gathered from the other side of the device;

Figure 12 is a view showing one form of the device embodying the invention wherein the material is being gathered in a pillar drawing operation to one side of the device;

Figure 13 is a view showing one form of the device embodying the invention wherein the material is being gathered in a pillar drawing operation on the other side of the device.

Referring now to a typical installation of my device illustrated in Figure 10, a scraper 1 of any suitable form, preferably bottomless, has a head line 2 connected therewith and a tail line 3 also connected therewith for reciprocable movement. The tail line passes over a sheave 4 opposite the turning point of the scraper and a sheave 5 near the starting point of the scraper operation. The head line 2 is engaged by a direction changing device 6 which may be a pulley. This direction changing device is connected with the end of a control line 7. This control line passes around a sheave 8. The direction changing devices 4, 5 and 8 are preferably fixed in position.

A portable controlling mechanism is provided for these lines, carried on a truck 9 having a pair of longitudinally spaced axles 10, 10 with supporting wheels 11, 11 thereon adapted to be run on suitable tracks. To enable this truck to traverse the average mine track which is relatively rough and uneven, the rear axle is solidly mounted to the truck while the forward axle is flexibly mounted to the truck by means of the springs 12, 12 interposed between the truck and the axle boxes 13, 13, as shown in Figure 3. This provides the equivalent of a three point suspension for the propelling mechanism, and while it allows the machine to travel over a

relatively rough track without derailing, it also affords a solid base for the loading mechanism at its rear end during the loading operation, where stability is especially desirable.

5 When the device is in operation this truck may be run to the entrance of a mine room as illustrated in Figure 10. A short section of track is placed on the floor and the truck is supported on this track. The truck is provided with three winding drums independently driven by a suitable motor which is here illustrated as an electric motor 14. Said motor is rigidly mounted to said truck rearwardly of the forward axles and forwardly 10 of the rearward axles and is contained within the lateral boundaries of the truck. The armature shaft 15 extends longitudinally of the truck and the motor is so placed that it requires a minimum of height in order that a 15 loading chute may be placed over the motor and rope actuating mechanism and still allow the device to be used in relatively low coal where the head room is limited. The compartments for the controller 16 and rheostat 17 are at opposite sides of the motor and are 20 cast integral with the motor shell and are also contained within the lateral boundaries of the truck 9. Said motor is connected by an armature pinion 18 to a gear 19 to rotate 25 a shaft 20 and bevel pinion 21. The bevel pinion 21 is meshed with a bevel gear 22 which is keyed to a drum shaft 23. In Figure 4 it may be seen that the drum shaft is hollow and is provided with holes 24 which lead to 30 the several rope drums and driving mechanism bearings. A lubricant may be injected into this shaft under pressure and when forced through the holes 24 lubricates the rope drums and driving mechanism bearings. 35 40 A tail line drum 25, head line drum 26 and control line drum 27 are loosely mounted on the shaft 23. In the preferred form shown the head line drum 26 is arranged in the center, and the tail and control line drums 45 on the right and left sides, respectively, this arrangement being especially adapted for co-operation with the ropes in the more usual operative positions thereof, as will herein-after more fully appear.

50 Suitable means are provided for driving each rope drum from the shaft 23, the means herein shown comprising a friction clutch for each rope drum. Said clutches are operated independently of each other so that any rope drum may be operated at any time independently of the other drums. This is an important feature in loading devices of the 55 scraper type having three ropes since it permits wide variations in the movement of the 60 scraper such as in cleaning up loose coal around corners or places distant from the ordinary path of the scraper; thus the scraper may gather coal which would otherwise have to be shoveled into its path, and it also may 65 be allowed to move out of its normal path

through the coal when loaded to avoid using the additional power necessary to pull the loaded scraper through the loose coal.

The construction of the clutches for each rope drum is substantially the same, with the exception that a brake is provided in connection with the head and tail rope drums and having interlocking engagement so as to be applied as the respective clutches are released, thus preventing the rope drums from overrunning and tangling up the rope as it is being unwound from its respective drum. This braking action is not sufficient to prevent rotation of the drum but is simply sufficient to take up slack on the idle rope and keep the rope taut. The control rope drum is provided with a brake which is independent of the clutch. The clutches herein comprise in each instance an expanding friction clutch of the single toggle shoe type. A flange 28 is integral with each rope drum. An outer periphery of this flange 29 serves as a brake drum while an inner periphery 30 serves as one face for a clutch. The other clutch face comprises two shoes 31, 31, which are covered with suitable friction material. Said shoes are pivoted at one extremity to a common point on a spider 32 by a pivot pin 33. Said spider is keyed to the shaft 23 and rotates with this shaft. Adjustable toggle 34 links 35 connect the other extremities of these shoes to a sliding piece 37 with pivot pins 35 and 36. Said piece 37 slides longitudinally in a guide 38 integral with the spider 32 and is actuated by a link 39 pivoted to this piece by a pin 40 and pivoted to a clutch collar 41 by a pin 42. Sliding of the clutch collar in one direction forces the sliding piece 37 in an outward direction and thus forces the clutch shoes 31, 31 against the inner periphery 30 of the flange 28 to apply the clutch and drive the rope drum. Sliding the collar in the opposite direction releases the pressure of the clutch shoes 31, 31 on the inner periphery of the brake drum and allows the rope drum to ride free on the drive shaft 23. This clutch collar is feathered to the shaft 23 and is actuated by a clutch fork 43 through a shifting collar 44. Said fork is actuated by suitable levers, which are herein shown as controlled from the right hand side of the machine. Hand levers 45 and 46 actuate the head and tail rope drum clutches respectively while a foot lever 47 actuates the control rope drum clutch. A spring 47^a is provided with the foot lever 47 to release the clutch when the foot pressure is removed from the lever.

The interlocking brake mechanism for operating the head and tail line drum clutches includes an arm 48 carried at the lower end of each clutch fork 43. A rod 50 connects this arm with the lower extremity 49 of a brake shoe 51. This connecting rod is preferably provided with a turn-buckle 50^a

to permit adjustment thereof. The upper extremity of the brake shoe 51 is connected to the truck frame by a rocking link 52 which rocks on a pin 53. Rocking of the clutch 5 fork 43 causes the rod 50 to rock the brake shoe 51 and thus apply or release the pressure on the brake drum 29.

Means are also provided for holding the control rope drum 27 against rotation when desired. In the construction shown I have provided a brake for this purpose consisting of the outer periphery 29 of said drum having thereon a brake band 55. One end of this brake band is connected to a fixed point 15 56. The other end is connected to one end of a crank lever 57 pivoted to the rod 58. The foot lever 59 is pivoted to the other end of this rod. Pressure on this lever rocks the rod 58 and the crank lever 57 and applies the 20 brake. A spring 59^a is provided tending to disengage this brake when pressure is released from the foot lever 59.

The drum drive shaft 23 is also connected for propelling this portable power device 25 through a sprocket 60 keyed to a collar 61 which is integral with a drum 62, loosely mounted on the shaft 23. The outer periphery of this drum 63 serves as a brake drum while the inner periphery 64 serves as a 30 clutch face. The same type of single toggle shoe type clutch hereinbefore described in connection with the rope drums, is used on this drum, therefore need not be described in detail. It will be seen that when the clutch is 35 applied, the drum 62 rotates with the shaft 23 and rotates the sprocket 60. A driving chain 65 engages this sprocket and drives a sprocket 66 keyed to the rearward axle 10 and thus rotates this axle. The forward and 40 rear axles are connected together by a sprocket 67, drive chain 68 and sprocket 69. The lever 70 operates this clutch from the rear end of the power device. A braking means is provided for this propelling mechanism. In the construction shown, I provide 45 a brake for this purpose consisting of the brake drum 63 having a brake band 71 thereon. Said brake is operated by a hand wheel 72. Rotation of this wheel in one direction 50 applies the brake while rotation in the other direction releases it.

The truck 9 is provided with an inclined chute or guide 73 for the scraper. This guide is arranged so that when the scraper reaches 55 the truck it is pulled up along this guide, carrying the material with it. The end of this guide is so placed that the material from the scraper is discharged into a receiving device such as a car 74. This chute is wide enough 60 to accommodate a relatively large scraper and the actuating mechanism for the scraper lines is completely contained beneath and within the lateral boundaries of the chute. This guide chute is preferably provided with a 65 detachable lower end section 75 which may be

moved out of the way when the truck is being transported, but which can be moved to the position shown in Figures 1 and 2 when the scraper is loading coal.

In the form shown this end section 75 is 70 made up of two sections 75^a and 75^b. These sections are detachably mounted to the forward end of the guide chute 73 by the projection 75^c which fits into the slots 75^a. An upper extension 76 is also provided, suitably supported for movable adjustment at the upper or rear end of the chute to provide more overhang when discharging material into cars. Herein, said extension is hinged and may be raised to the position shown in Figure 80 1 or lowered when travelling. When it is desired to move the truck, this end section is removed and placed on the guide chute.

A set of stops 77 are provided with this chute to stop the scraper when it has reached the end of its run on the guide chute. These stops each consist of a rod 78 which is mounted for longitudinal movement in brackets 79 and 80. One end 81 of the rod is bent at right angles to extend into the path of the scraper. 85 This end slides in the slot 82 in the guide chute 73. A collar 84 is fixed to the rod and a spring 83 is interposed between the collar and the bracket 79. It will thus be seen that as the scraper hits the projecting ends 81 of the rods 78, the springs 83 are compressed and the scraper is stopped.

The loading device is also provided with an extension arm 85 similar to that shown and described in Davis application Serial Number 352,413, filed June 19, 1920, having a direction changing device or pulley 86 over which the head line 2 passes. This extension arm is so arranged that it may be slid inwardly during the travelling operation of the loading mechanism. This arm is supported for longitudinal adjustment in a socket (not shown) at the top of the guide chute 73. The lower end of this arm projects from this socket and is beveled and enlarged so as to strike the end of the socket and prevent the complete withdrawal of the arm. A locking piece (not shown) is provided to hold this arm in position during the loading operation. A head line 2 passes from the scraper about the 100 direction changing device 86 over the guide roller 87 to the head line drum 26. It will be seen that this line comes from the top of its drum 26 and extends rearwardly, while the tail line 3 and control line 7 come from the bottom of their respective drums, and extend forwardly. Thus the rotation of the shaft 23 in the proper direction will wind the rope on any drum that is clutched to this shaft.

In Figure 2 the tail line 3 passes from the bottom of the rope drum 25 over the rollers 88 and 89 and through the sheaves 90 and 91. As seen in Figure 1, the control line passes from the bottom of the drum 27 over the rollers 92 and 93 and through the sheaves 94 and 120 130

95. These sheaves are detachably fastened to the loading device and are mounted so they will have a certain amount of flexibility and will tend to follow the draft ropes as shown in Figure 9, which illustrates details of construction of sheaves 91 and 95. From this figure it will be seen that a sheave block 98 is pivotally mounted to the eyebolt 100, eccentric of its central axis, by a pin 99. The inside diameter of the eye in the eyebolt 100 is larger than the outside diameter of the pin 99 to allow free pivotal movement between the pin and the eyebolt. The sheaves 91 and 95 are fastened to laterally extending brackets 105 which are detachably connected to angle bars 107 at opposite sides of the guide chute 73. These brackets are held in place by set screws 108. These set screws have a relatively large head and are so made that they can be easily removed by hand. Similarly, sheaves 96 and 97, when used as in Figures 7 or 8, are supported by detachable brackets 106, 106 secured to angle bars 107 rearwardly of brackets 106, as shown. The sheaves 90 and 94 are fastened to the brackets 101. These sheaves may be reversed when desired (Figures 7 and 8) by removing the securing bolts 102 from the apertures 103 and replacing said bracket in a reversed direction by bolting in the apertures 104. Each bracket is provided with two apertures for the sheave eyebolts so the sheaves may remain in the same lateral position with respect to each other after they are reversed. The sheaves 96 and 97 (Figures 7 and 8) are added to be used in pillar drawing or retreat work as will hereinafter appear.

The use and operation of my invention is as follows:

A typical installation of the apparatus is shown in Figure 10, in which the truck with its incline and control mechanism is run to the mouth of a mine room, which is being worked in accordance with the room and pillar system of mining. The truck is preferably placed on a short section of track 109 arranged in the room neck or entrance 110 at right angles to the track in the haulage way. The direction changing devices 4, 5, 6 and 8, with the guide or deflector 111 are placed in position as shown. The coal has been mined from the working face or wall 112 and is lying on the floor near this wall. The scraper is then brought to the position shown in Figure 10. The pulling forward of this scraper causes it to be loaded with loose coal. When this scraper is full of coal it is necessary to turn it so that it can be moved toward the entrance of the room. This turning must be gradual and is accomplished by allowing the direction changing device 6 to move away from the direction changing device 8. These movements are controlled at the loading device as follows: At the starting point shown in Figure 10, the friction clutch for the head line drum 26 is thrown in

by pulling on the lever 45. This causes the drum 26 to rotate and wind in the head line and thus move the scraper forwardly. At the same time the operator's foot is on the control rope drum brake lever 59. This holds the direction changing device 6 stationary. When the scraper reaches the direction changing device 6, the pressure on the foot lever is released and the control rope is unwound, as the head rope is drawn in, moving the direction changing device 6 away from the direction changing device 8. This causes the scraper to turn away from the room and proceed toward the room neck. The deflector 111 is used to aid the scraper in turning the corner and prevent it from hitting the props or other obstructions. The tail rope is engaged by this guide or deflector after the scraper has been headed toward the room neck. The continuing winding of the drum 26 pulls the scraper on the guide chute 73 where it engages stops 77 and discharges its load into the car 74.

After the scraper hits the stops 77, the movement of the scraper is reversed. This is accomplished by manipulating the lever 45 to disengage the head rope drum clutch and using lever 46 for engaging the tail rope, and thus wind in the tail rope 3. During a portion of this backward travel the tail line 3 engages the deflector guide 111 until the scraper itself engages and passes around said guide. As the tail line is being wound on its drum 25 the control line clutch is also engaged to wind said line on its drum 27. When the direction changing device 6 nears the direction changing device 8 the clutch on the control line drum is released and pressure is applied to the control line foot lever 59 to apply the control drum brake and hold the direction changing device 6 in position. While this is being done the tail line continues to draw the scraper back to its starting point.

In case it is desired to load from the left of the machine as in Figure 11, the position of the control rope and tail rope may be changed without changing the normal functions of the three drums. In this figure it is seen that the control and tail ropes are rearranged so as to cross each other, the control rope being paid off of the right hand side of the machine while the tail rope is paid off of the left hand side of the machine. In order to change the position of these ropes it is simply necessary to reverse the sheaves 90 and 94 by removing the angle brackets from the apertures 103 and replacing them over the apertures 104 in a reversed position. The ropes may then be crossed under the chute 73 to pay off the ropes as required.

My device may also be used in retreating systems of mining as distinguished from advancing systems of mining. Figures 12 and 13 show the device loading coal in one form of a retreating system of mining while the

Figures 7 and 8 show enlarged details of the sheave and rope arrangement. Therefore, the convenience and advantage of the auxiliary removable sheaves 96 or 97 for each side of the machine projecting beyond the lateral boundaries of the device may be clearly seen in this system of mining. The principle of turning the scraper and controlling the ropes is the same in this system of mining as in the advancing system of mining. The location of the sheaves, direction changing devices and control and tail ropes are the only changes necessary. The control and tail ropes are both paid off the same side of the machine.

This is accomplished by reversing the sheave 90 and inserting the third sheave 96 between the sheaves 94 and 95 (Figures 7 and 12). The tail line therefore passes through the sheave 90 and 96 around the direction changing devices 4 and 5 to the rear end of the scraper 1. The control line 7 passes through the sheaves 94 and 96 around the direction changing device 8 to the movable direction changing device 6. When the material is to be gathered on the left hand side of the loader, the position of the control and tail ropes are reversed so they pay off the opposite side of the device, as can be seen from Figures 4 and 13.

I have described in detail a particular construction embodying my invention but it is of course evident that the construction may be varied in many particulars without departing from the spirit of the invention as set forth in the claims hereto attached and I therefore do not limit myself to the construction shown.

I claim as my invention:

1. A device for handling loose material comprising a scraper with draft means for moving the same, a control line, a portable power device for said scraper, an incline extending over said power device, drums within the limits of said incline at the rear end thereof, guide devices for said draft means comprising a pair of sheaves on opposite sides of the lateral boundaries of said incline, the sheaves in each pair having their axes offset from each other and including an inner sheave and an outer sheave, said sheaves having pivotal mounting on said portable power device eccentric of their axes and the inner sheaves having reversible connections to extend toward one or the other side of said portable power device, and auxiliary sheaves pivotally connected eccentrically of their axes on each side of said incline and detachably connectible intermediate each of said first mentioned pair of sheaves.
2. In combination with a loading device, a scraper, a portable power device for said scraper including a truck supported on wheels and axles, draft mechanism therefor comprising a driving motor having a shaft placed longitudinally of said power device, a sec-

ond shaft parallel with said motor shaft, a geared connection between said motor shaft and said second shaft, a third shaft perpendicular to said second shaft lying in a horizontal plane, a bevel gear connection between said third shaft and said second shaft, winding devices comprising three rope drums mounted on said third shaft and driven therefrom, clutch mechanism for each of said rope drums, braking means for one of said rope drums operable independently of said clutch mechanism, braking means for the two remaining drums having interlocking engagement with said clutch, means on said shaft connectible with said wheels for propelling said truck, means for selectively driving said truck propelling mechanism or any of said rope drums, and braking means for said truck propelling mechanism on said shaft.

3. A device for handling loose material comprising a scraper with draft means for moving the same, a control line for controlling the movement of said scraper, said control line being independent of said draft means, a truck, an incline extending over said truck, a plurality of drums for operating said draft and control means, said drums being within the limits of said incline and near the rearward end thereof, and guide devices for said draft means comprising a pair of sheaves on each side of said incline, the sheaves in each pair having their axes offset from each other, and each of said sheaves having a flexible pivotal mounting on said truck eccentric of their axes.

4. A device for handling loose material comprising a scraper with draft means for moving the same, a control line, said control line being independent of said draft means, a truck, an incline extending over said truck, a plurality of power driven drums for operating said draft and control means, said drums being within the limits of said incline and near the rearward end thereof, and guide devices for said draft and control means near the forward end of said incline comprising a pair of sheaves on each side of said incline, the sheaves in each pair having their axes offset from each other whereby said sheaves form an inner sheave and an outer sheave, each of said sheaves having a flexible pivotal mounting on said truck eccentric of their axes and the inner sheaves having reversible connection to extend toward one or the other side of said truck.

Signed at Chicago, in the county of Cook and State of Illinois, this 1st day of March, A. D. 1926.

ALFRED B. ESSELTINE.
